UNITED STATES PATENT OFFICE

2,315,555

TREATMENT OF GAS DISTRIBUTION SYSTEMS

John R. Skeen, Philadelphia, Pa., assignor to The United Gas Improvement Company, a corporation of Pennsylvania

Application July 22, 1939, Serial No. 285,942

6 Claims. (Cl. 48—190)

This application is a continuation-in-part of my copending application Serial Number 236,822, filed October 24, 1938, and pertains generally to the treatment of the interiors of gas mains or other gas enclosures with a liquid mixture containing a non-cyclic high boiling aliphatic alcohol and monophenyl ether of ethylene glycol.

Systems for the distribution of gas include conduits or mains which are usually laid underground, and which comprise sections of pipe joined together by means of welding, by means of packed joints, by means of screw joints, or otherwise.

The welded joint is a more recent development and is used chiefly to join pipe sections of steel or iron, other than cast iron.

Older mains are usually made up of cast iron pipe sections joined by means of bell and spigot or other similar joints. These joints are usually packed with hemp, jute, flax or other cellulosic material which in turn is backed up with lead or cement or other material in a well known manner.

Over a period of years the water condensed from wet gas together with other constituents of the gas such as carbon dioxide, hydrogen sulphide, hydrocyanic acid, naphthalene, and so forth, have in many instances, caused extensive corrosion of the interior walls of the mains. The products of corrosion have accumulated on the walls of the mains and, in many instances, large quantities have become disconnected and have collected along the bottom.

Due to the presence of relatively large quantities of moisture, largely responsible for the corrosion in the first instance, the products of corrosion were maintained in a wet condition and did not tend to form dust in any appreciable quantity.

Therefore, until high pressure distribution came into practice, and while the use of natural gas or natural gas mixtures were less widespread, very little difficulty was experienced with the formation of dust in mains from the products of corrosion.

In other words, as long as a main is used for distributing ordinary wet manufactured gas very little trouble with dust resulting from corrosion is experienced. However, when the service is changed over to a manufactured gas of low moisture content, or over to natural gas or natural gas mixtures which are characterized by very low moisture content, the moisture on and in the

corrosion products dries out and such products become a serious source of dust.

5 The presence of considerable quantities of dust in the gas flowing through the mains of a distribution system is very undesirable because dust tends to clog up customer service connections, interferes with the proper operation of meters, and tends to clog up burners and pilot outlets.

10 Under extreme conditions corrosion may be so severe as to form a serious obstruction in the main itself by reducing its effective cross-sectional area such as by the accumulation of dust in piles in the main.

A number of methods of correcting dust troubles have been proposed and used.

For instance, excavations have been made at suitably spaced points along the main, say, every 300 feet, the main severed at each excavation and the accumulation removed mechanically.

20 This has been done by dragging a ball of chain back and forth through the disconnected section and increasing the size of the ball as more and more of the products of corrosion have been removed. In some instances, a cutter has been substituted for the ball of chain.

In another method a compressor is conformed to function as a suction device for sucking air through the disconnected main section, and the 25 dust is collected in a bag in a manner customary in the operation of the ordinary vacuum cleaner.

It will be appreciated that either of the foregoing methods of overcoming dust troubles is very expensive in view of the immense amount 30 of labor involved. Furthermore, both methods put the main out of service during the treatment.

The use of steam for dust laying has the disadvantage that the deposited moisture dries out 35 as soon as steaming is stopped. As far as I am aware the same also applies to the fogging of oil into the mains, since the oil which it has been necessary to use for successful fogging has had to be so light as to make it appreciably volatile.

Furthermore, since the corrosion products comprise not only ordinary iron rust but also a variety of other compounds resulting from the action of hydrogen sulfide, hydrocyanic acid, 40 naphthalene, and other corrosive substances, the problem of wetting down the dust, of wetting the main wall, and of thoroughly spreading a dust laying liquid becomes a major factor.

Moreover, in many distribution systems tar, 45 resin and gum have been deposited from the gas

and operate to exclude many types of treating substances from contact with sources of dust and/or with joint packings where treatment of the latter is desired such as with a liquid capable of swelling hemp and jute to the same extent as water.

A feature of the invention is to provide an improved dust laying and/or joint sealing composition which possesses sufficient solvent power with respect to tar, resin and gum to cause the treating constituent or constituents of the composition to wet and be absorbed by accumulations of dust and/or cellulosic fiber packing with sufficient rapidity for practicable purposes.

Another feature of the invention is to provide a dust laying and/or joint sealing composition having improved wetting qualities not only for tar, resin and gum, but also for the metal of the main walls.

Another feature of the invention is to provide a new article of manufacture and a process for making the same.

Other features of the invention will become more apparent to persons skilled in the art as the specification proceeds.

I have discovered that a liquid mixture comprising a non-cyclic high boiling aliphatic alcohol and monophenyl ether of ethylene glycol is excellently adapted (a) to wet, hold and/or bind dust particles and to coat dust sources; (b) to soften or dissolve tar, resin and/or gum which may cover dust sources or form incrustations with dust deposits; and (c) to spread and climb upon the walls of the gas main and throughout the sources of dust.

The non-cyclic high boiling aliphatic alcohol may be one which is capable of swelling cellulosic fiber packing to the same extent as water of which ethylene glycol, diethylene glycol, mono methyl ether of ethylene glycol, mono methyl ether of diethylene glycol and glycerine are outstanding examples.

The tar resin and gum penetrating power of monophenyl ether of ethylene glycol and its wetting and climbing action greatly improve the action of such treating liquids by dissolving or softening tar resins and gum on the packing and assisting the swelling agent to climb and wet the packing.

Any desired quantity of my mono phenyl ether of ethylene glycol may be admixed with such dust laying and/or cellulosic fiber swelling liquids according to the results desired, such as from 5 to 20% in the case of cellulosic fiber swelling liquids.

When more drastic treatment is required to penetrate incrustations larger percentages are recommended.

The treating liquid may be applied to the interior surface of a pipe section during or after the assembly of the pipe sections to form the main. This may be accomplished in any desired manner such as by spraying, brushing, or otherwise.

If the main is already in service, sections of the main may be "blocked off" by means of inflated bags or other means, and the sections then completely filled with the liquid after which the liquid can be drawn off and re-used.

On the other hand, the liquid may be sprayed into the gas by the fogging procedure earlier mentioned so that the dust sources absorb the liquid from the gas stream or, in other words, so that the liquid is deposited from the gas stream onto the sources of dust.

In another method of application the liquid is

introduced into the main at high points and allowed to run by gravity to low points where the excess can be drawn off. An examination of mains treated in this manner shows that my composition has greatly improved climbing properties.

Another method comprises inserting a long length of hose into the main with a spray at its end, or with a plurality of sprays distributed along its length, and pumping the treating liquid into the hose while withdrawing the hose either continuously or intermittently or otherwise, or while the hose remains stationary.

In the last three methods of application service on the line need not be interrupted. Dust sources become coated with the treating liquid. The wetting of finely divided material causes it to be bound together in a mass which prevents it from rising in a dust regardless of the velocity of the gas travelling through the main. The clogging of mains, meters, regulators and appliance is thus effectively prevented.

A typical gas main is illustrated in the drawing in which:

Figure 1 is a side elevation, partly in section, illustrating a gas main; and

Figure 2 is a cross-section on line 2-2 of Figure 1.

In the drawing the gas main 10 is shown with a joint comprising bell 11 and spigot 12 fitting within said bell and spaced therefrom. In the space between the bell and the spigot is cellulosic fiber packing 13 which may be tarred or untarred, and a seal 14 of lead or other suitable material for holding the packing in place. The treating liquid 15 as illustrated is being run through the main by gravity. It contacts the bottom of the main and any deposits accumulated thereon. It also contacts the packing at space 16 which space is left between the spigot and the shoulder of the bell to provide for expansion and contraction due to temperature changes. The packing absorbs the liquid at 16 and the liquid climbs and is carried up in the packing as shown by the outer group of arrows in Figure 2. If one or more substance capable of swelling the packing such as ethylene glycol, diethylene glycol, mono methyl ether of ethylene glycol, mono methyl ether of diethylene glycol and glycerine is present the packing is swollen to substantially the same extent as with water. The treating liquid also climbs up the metal walls of the main as illustrated by the inner group of arrows in Figure 2 to coat dust sources in addition to those along the bottom of the main.

The bulk of the treating liquid, of course, remains in the main only during the time that its flow from the point of introduction to the point of removal which usually is the nearest drip.

Any other means for applying the treating liquid to the packing and/or to the interior of the conduit may be employed. For instance, in the case of large diameter mains the level of the liquid 15 may be raised or may be made to fill the entire main if desired, or the spray or fogging methods may be employed.

In the case of a welded main, or other main having joints in which cellulosic fiber packing is not present, the treatment becomes primarily one of dust laying. Likewise, when my mono phenyl ether of ethylene glycol is employed with those non-cyclic high boiling aliphatic alcohols which are incapable of swelling the packing such as certain of those disclosed in my parent application, the treatment becomes more essentially one

of dust laying regardless of the type of main treated, except in so far as a liquid seal is formed in the interstices of the packing.

While the invention has been described in connection with gas mains it is to be understood that it is applicable to any part of a gas distribution system wherein similar problems may arise. It is also to be understood that the various agents referred to herein may be used either in the pure or commercially pure form, or in any other suitable form including the commercial and crude forms.

It is to be understood that the above particular description is by way of illustration and that changes, omissions, additions, substitutions, and/or modifications might be made within the scope of the claims without departing from the spirit of the invention.

For instance, other tar penetrating agents or other suitable material may be added in addition to my monophenyl ether of ethylene glycol.

The terms "comprises" and "comprising" are used in the claims in their usually accepted meanings which do not exclude other steps or the presence of substances other than those specifically recited.

I claim:

1. A method for reducing gas leakage through cellulosic fibrous packing in a joint of a gas distribution system, comprising impregnating said packing with a cellulosic fiber swelling agent selected from a group consisting of ethylene glycol, diethylene glycol, mono methyl ether of ethylene glycol, mono methyl ether of diethylene glycol, and glycerine by bringing said agent into contact with said packing in the presence of mono phenyl ether of ethylene glycol.

2. A method for laying dust in the interior of a gas distribution conduit having dust deposits along the bottom thereof, comprising enveloping said dust deposits with a dust laying liquid se-

lected from a group consisting of ethylene glycol, diethylene glycol, mono methyl ether of ethylene glycol, mono methyl ether of diethylene glycol, and glycerine by bringing said liquid into contact with said dust sources in the presence of mono phenyl ether of ethylene glycol.

3. A joint in a gas distribution system comprising spaced cooperating elements, cellulosic fibrous packing such as jute and hemp between said cooperating elements positioned to form a seal, and a liquid mixture absorbed by said packing, said liquid mixture comprising mono phenyl ether of ethylene glycol and at least one of a group consisting of ethylene glycol, diethylene glycol, mono methyl ether of ethylene glycol, mono methyl ether of diethylene glycol, and glycerine.

4. A joint in a gas distribution system comprising a bell, a spigot positioned within and spaced from said bell to form an annular space, an annular ring of cellulosic fibrous packing in said annular space and continuously contacting said bell and spigot on its outer and inner peripheries respectively, and a liquid mixture absorbed by said packing, said liquid mixture comprising mono phenyl ether of ethylene glycol and at least one of a group consisting of ethylene glycol, diethylene glycol, mono methyl ether of ethylene glycol, mono methyl ether of diethylene glycol, and glycerine.

5. A method for treating the interior of a gas distribution system which comprises applying to the interior of said system a liquid mixture comprising a non-cyclic high boiling aliphatic alcohol, and monophenyl ether of ethylene glycol.

6. A gas conduit having interior dust sources wetted down with a liquid mixture comprising a non-cyclic high boiling aliphatic alcohol, and monophenyl ether of ethylene glycol.
